UNITED STATES PATENT OFFICE.

ADDISON JENKINS, OF KOKOMO, INDIANA, ASSIGNOR TO D. C. JENKINS GLASS COMPANY, OF KOKOMO, INDIANA, A CORPORATION.

DESIGN FOR A LAMP-CHIMNEY.

47,301.

Specification for Design.

Patented May 4, 1915.

Application filed January 13, 1915. Serial No. 2,082. Term of patent 14 years.

To all whom it may concern:

Be it known that I, ADDISON JENKINS, a citizen of the United States of America, residing at 622 West Mulberry street, in the city of Kokomo, in the county of Howard and State of Indiana, have invented a new and original and ornamental Design for a Lamp-Chimney, of which the following is a specification, reference being had to the accompanying drawing, forming a part thereof.

The figure is an elevation of the lamp chimney.

I claim:

The ornamental design for a lamp chimney as shown.

ADDISON JENKINS.

Witnesses:

A. G. STEELE,
HOWARD C. JENKINS.
